UNITED STATES PATENT OFFICE.

CHARLES A. COVEY, OF SAN ANTONIO, TEXAS, ASSIGNOR OF ONE-FOURTH TO CLAUDE V. BIRKHEAD.

MULTIPLE-BLOCK MOLD.

Application filed July 5, 1927. Serial No. 203,652.

The invention relates to improvements in cement block molds designed for the formation of a plurality of blocks, and the principal object of the invention is to provide a 5 mold constructed from a plurality of sections which may be assembled to permit the simultaneous molding of a desired number of blocks.

Further objects are to provide unique 10 means for connecting the mold sections with each other and to provide novel means for shaping the tops of the blocks to interfit with the bottoms of overlying blocks.

A still further aim is to provide a construction 15 which will be rather simple and inexpensive, yet will be efficient, reliable and in every way desirable.

With the foregoing in view, the invention resides in the novel subject matter herein- 20 after described and claimed, the description being supplemented by the accompanying drawings.

Fig. 1 is a perspective view showing a 25 number of the mold sections assembled.

Fig. 2 is a disassembled perspective view of the parts shown in Fig. 1.

Fig. 3 is a transverse sectional view on line 3-3 of Fig. 1.

Fig. 4 is a detail horizontal section sub- 30 stantially on line 4-4 of Fig. 1.

Fig. 5 is a perspective view of one of the blocks formed by the mold.

Fig. 6 is a perspective view showing a 35 number of the blocks laid with others in the formation of a wall.

In the drawings above briefly described, the preferred form of construction has been illustrated. This construction will be herein specifically described, with the under- 40 standing however, that within the scope of the invention as claimed, variations may be made.

The numeral 6 designates a relatively long 45 rectangular side wall reinforced at its upper and lower edges by angle metal 7-8. Dis- posed in spaced parallel relation with the long side wall 6, is a relatively short wall 9. One transverse wall 10 is rigidly joined to one 50 end of the short side wall 9, and projects laterally in one direction therefrom, to one end of said side wall 6. Rigidly joined to the other end of the short side wall 9, is a second transverse wall 11 which projects in the opposite direction from the wall 10, said one trans- 55 verse wall 10 and said second transverse wall

11 being preferably of substantially plano-convex form in transverse section or plan view. A third transverse wall 12 is rigidly joined to the other end of the long side wall 6, that is, to the end of this wall remote from the transverse wall 10, and the angle metal reinforcements 7-8, preferably extend along the outer side of this transverse wall 12.

A second relatively long longitudinal wall 6^a is laterally spaced from the free edges of the transverse walls 11 and 12, in overlapping relation with the long side wall 6. A second relatively short side wall 9^a is disposed in spaced parallel relation with the long side wall 6^a and one end of this second short wall 9^a is provided with a fourth transverse wall 13 which is rigidly joined thereto and projects laterally to one end of the second long side wall 6^a. The other end of the second short wall 9^a is provided with a fifth transverse wall 14, rigidly attached to said wall 9^a and projecting laterally therefrom into overlapping relation with the third transverse wall 12. The other end of the second long side wall 6^a, that is the end remote from the fourth transverse wall 13, is provided with a sixth transverse wall 15 which is rigidly joined thereto and projects therefrom into overlapping relation with the second transverse wall 11.

The two long side walls 6-6^a and the six transverse walls 10-11-12-13-14-15, together with certain connecting means hereinafter described, provide a mold which will form one block, and portions of this 90 mold co-operate with other mold sections hereinafter described, in the formation of a second block. Similarly, these last named mold sections may be coupled to others to form still other blocks and the line of molds 95 may be extended to any desired length.

A third relatively long side wall 6^b is outwardly spaced from the second short side wall 9^a and abuts the third transverse wall 12, being connected thereto by means herein- 100 after explained. A fourth relatively long side wall 6^c is disposed in overlapping relation with the wall 6^b and is provided at one end with a seventh transverse wall 16 which is rigidly attached to said wall 6^c and ex- 105 tends into overlapping relation with the fourth transverse wall 13, being interposed between this wall 13 and the adjacent end of the second long side wall 6^a. Hence, the same relation which exists between the third trans- 110

verse wall 12, the fifth transverse wall 13 and the third long side wall 6^b, exists between the second long side wall 6^a, the fourth transverse wall 13 and the seventh transverse wall 16. 5 An eighth transverse wall 17 has been shown rigidly joined to the wall 6^b and projecting therefrom toward the wall 6^c.

Upper and lower lugs 18 and an eye 19 are formed at the free edge of each of the 10 transverse walls 10, 11, 13 and 14. The free edge portion of each of the transverse walls 12, 15, 16 and 17, is formed with upper and lower groups of slots 18^a and between said slots with another slot 19^a. The ends of the 15 relatively long side walls 6, 6^a, 6^b and 6^c, remote from the last named transverse walls, are each provided with a lateral flange or lug 20 having slots 21 and 21^a. Pivoted to each of these long side walls, near the lug 20, is an arm 22 whose pivot is such as to 20 also permit longitudinal sliding of said arm. The free end of this arm carries one or more wedges 23.

To connect the first long side wall 6 to the 25 first transverse wall 10, the eye 19 of the latter is passed through the slot 21 in the lug 20 of said wall 6 and the lugs 18 are passed through the slots 21^a, and the wedge 23 is then forced or driven through the eye, 30 as clearly shown at the left of Fig. 1.

To connect the transverse walls 12—14 with each other and with the third long side wall 6^b, the lugs 18 of the fifth transverse wall 14 are passed through the slots 18^a of the transverse wall 12, and through slots 21^a of lug 20 of wall 6^b, the eye 19 of said wall 14 is passed through the slot 19^a of the wall 12 and also through the slot 21 in the lug 20 of the third long side wall 6^b. Then, the 40 wedge 23 associated with this side wall, is forced or driven through the eye as shown at the central portion of Fig. 1.

The transverse walls 11—15 are connected with each other merely by passing the lugs 45 18 and the eye 19 of the wall 11 through the slots 18^a—19^a of the wall 15. If desired, however, a wedge or the like may then be inserted through the eye.

The second long side wall 6^a, the fourth 50 transverse wall 13 and the seventh transverse wall 16, are connected with each other in exactly the same manner as the walls 12—14—6^b, are connected.

While the reinforcements 7—8 have been 55 described only in connection with the long side wall 6 and the attached transverse wall 12, it will be observed that this same construction is duplicated with other sections of the mold. Both the upper and lower angle bars 60 are formed with slots 24 and the slots of the lower bars are engageable with lugs 25 on a base 26, assisting in properly positioning the mold sections on said base. In this connection, it may be stated that the slots 24, like 65 the slots 18^a, are disposed in groups. This

permits slight lateral variation of the width of the molds, as occasion may demand. Moreover, it will be seen that by providing duplicate slot arrangements at the upper and lower portions of the mold sections, these 70 sections may be used with either longitudinal edge contacting with the base.

The mold formations herein disclosed, will produce blocks of S-shape in plan view, as 75 shown in Fig. 5. I prefer to provide both the top and the bottom of each block with a rib 27 and a recess 28, so that the blocks may interlock with each other when building a wall. To form the ribs and grooves at the 80 bottoms of the blocks, depressions 29 and ridges 30 are formed on the base 26. To provide the ribs and grooves for the tops of the blocks, a plurality of plates such as that shown at 31 in Figs. 1, 2 and 3, are employed. Each plate is provided with oppositely 85 depressed portions 32—33 to produce the desired formations. This plate is preferably of a diamond shape and its four corners are provided with rigidly attached pins 34. These pins are receivable in openings 35 90 formed at desired points in the upper edges of a number of the mold walls.

It will be understood that only a portion 95 of the construction which may be in some instances used, is herein illustrated, but the remainder of such construction is merely duplication of the portions illustrated and hence need not be shown or described. It will be obvious however that the mold may be extended to any desired length for forming the desired number of blocks at a single 100 operation.

The blocks produced by the mold form no part of the present invention but are very 105 advantageous in the construction of all kinds of walls, it being of course clear that they must be used in connection with appropriate corner blocks formed by other desired molding means. The corner construction of the wall may if desired be reinforced and cement-filled as shown in Fig. 6, and it will also be obvious that the individual blocks may be reinforced if desired. Moreover, by forming curved longitudinal walls for the mold, curved blocks for silos and the like may be 110 cast in said mold.

I claim:

1. In a block mold, two parallel relatively long and short side walls, one transverse wall joined to one end of the short side wall and projecting to one end of the long side wall, a second transverse wall joined to the other end of said short side wall, a third transverse wall joined to the other end of said long side wall, said second and third transverse walls projecting laterally in the opposite direction from said one transverse wall; a second relatively long side wall and a second relatively short side wall disposed in parallel relation, 120 a fourth transverse wall projecting laterally 125 130

- from one end of said second short side wall to one end of said second long side wall, a fifth transverse wall projecting from the other end of said second short side wall to said third transverse wall, a sixth transverse wall projecting from the other end of said second long side wall to said second transverse wall, means detachably connecting the second and sixth and the third and fifth transverse walls, and means detachably connecting the first and fourth transverse walls to the first and second long side walls respectively.
2. In a block mold, two parallel relatively long and short side walls, one transverse wall joined to one end of the short side wall and projecting to one end of the long side wall, a second transverse wall joined to the other end of said short side wall, a third transverse wall joined to the other end of said long side wall, said second and third transverse walls projecting laterally in the opposite direction from said one transverse wall; a second relatively long side wall and a second relatively short side wall disposed in parallel relation, a fourth transverse wall projecting laterally from one end of said second short side wall to one end of said second long side wall, a fifth transverse wall projecting from the other end of said second short side wall to said third transverse wall, a sixth transverse wall projecting from the other end of said second long side wall to said second transverse wall; a fifth side wall outwardly spaced from said second short side wall, means detachably connecting said fifth side wall and said third and fifth transverse walls; a sixth side wall having a seventh transverse wall extending to said fourth transverse wall, means detachably connecting said seventh and fourth transverse walls and said second long side wall, means detachably connecting said second and sixth transverse walls, and means detachably connecting said one transverse wall to said one long side wall.
3. In a block molding means, a sectional mold comprising a relatively wide molding portion and a comparatively narrow molding portion projecting from one end thereof; and a longitudinal wall connected to said end of said relatively wide molding portion and disposed in spaced parallel relation with said comparatively narrow molding portion, the latter and said wall co-operating in forming parts of another mold.
4. In a block molding means, a sectional mold comprising a relatively wide molding portion and a comparatively narrow molding portion projecting from one end thereof; a longitudinal wall connected to said end of said relatively wide molding portion and disposed in parallel relation with said comparatively narrow molding portion, and a wall connected to the outer end of the latter, said two walls and said relatively narrow molding portion forming parts of another mold.
5. In a block mold, a transverse wall having an outwardly projecting lug and an outwardly projecting eye, another transverse wall overlapping the first named wall and having openings through which said lug and eye project, a longitudinal wall abutting said other transverse wall and having a lateral lug formed with an opening through which said eye projects, and a fastener passing through said eye to secure the three walls in assembled relation.
6. In a block mold, two overlapped walls, one wall being provided with a lug and an eye projecting in the same direction and the other wall having openings through which said lug and eye project, and a fastener passing through said eye to hold the walls in assembled relation.
7. In a block mold, two walls at an angle to each other, one of said walls having a lug formed with an opening and the other wall being provided with an eye passing through said opening, a wedge received in said eye, an arm carrying said wedge, and means pivotally and slidably connecting said arm to said one wall.
8. In a block mold, a longitudinal wall having transverse walls rigidly joined to and projecting laterally in opposite directions from its ends, each of said transverse walls being provided with a lug and an eye projecting from its inner side for the purpose set forth.
9. A block mold embodying vertical walls having openings in their upper edges and a horizontal plate of small area compared with the horizontal area within said mold, said plate having pins receivable in said openings and being provided with means for shaping a restricted part of the top of the block to interfit with a restricted part of another block.

In testimony whereof I have hereunto affixed my signature.

CHARLES A. COVEY.
